CLAIM

The ornamental design for a pressure transducer housing, substantially as shown and described.

DESCRIPTION

FIG. 1 is a perspective view of an ornamental design for a pressure transducer housing;

FIG. 2 is a side elevational view of a first side of the ornamental design;

FIG. 3 is a side elevational view of a second side of the ornamental design, which second side is opposite the first side;

FIG. 4 is a side elevational view of a third side of the ornamental design;

FIG. 5 is a top plan view of the ornamental design; and, FIG. 6 is a bottom view of the ornamental design.

Broken lines in the illustrations of the drawing indicate unclaimed parts of the article that are not part of the design illustrated herein.

1 Claim, 5 Drawing Sheets
